UNITED STATES PATENT OFFICE.

ERNEST S. JEFFERIES, OF HAMILTON, ONTARIO, CANADA.

ELECTRIC METAL-STOCK HEATER.

Application filed December 6, 1926. Serial No. 153,000.

The invention relates to electric heaters adapted to automatically heat and deliver pieces of metal stock for the performance of some operation thereon, such as heading or drop forging. In my copending application, Serial No. 682,749, filed December 26, 1923, there is disclosed such a heater, of a rotary type, and the present invention contemplates an improved machine adapted to operate on a vertical axis instead of a horizontal axis, as in the former machine.

The general object of the present invention is to so improve a heater of this type as to greatly increase its reliability of performance; a particular object of the invention being to provide an electrically balanced transformer structure capable of handling very heavy currents, so that the stock may be heated and delivered at a rapid rate without overheating the windings. Further objects of the invention comprise the cooling of the oil in the transformer tank by a novel arrangement of water piping, and the cooling of the several electric contacts by direct contact of the cooling water therewith.

Other objects and advantages of the invention will hereinafter appear, reference being had to the accompanying drawings which show an illustrative embodiment of my invention, and in which

Fig. 1 is a front elevation with one half the machine being shown in section.

Fig. 2 is an elevation of the machine from the right hand side of Fig. 1.

Fig. 3 is a plan view.

Fig. 4 is a horizontal sectional view taken partly along the line 4—4 of Fig. 1, showing the construction of the transformer parts, the piping being omitted.

Fig. 5 is a developed plan view on an enlarged scale, showing the action of the stock transferring devices.

Fig. 6 is a sectional view on the line 6—6 of Fig. 5.

Fig. 7 is a wiring diagram, illustrating the transformer connections.

Fig. 8 is an enlarged sectional view through the water cooled contacts.

Fig. 9 is a fragmentary showing of certain gearing.

Fig. 10 is a side elevation of the top of

the machine, showing a modified form of feeding and cleaning device.

Fig. 11 is a front elevation of the apparatus of Fig. 10.

Fig. 12 is an enlarged sectional view of the feeding cage taken on the line 12—12 of Fig. 11.

Like reference characters refer to like parts in the different figures.

Referring to Figs. 1, 2 and 3, the machine is mounted on a base 1, which, together with the uprights 2 and a top-piece 3, constitutes a frame for the machine. A vertical hollow shaft 4, which carries the rotating elements of the machine, is journaled in the base 1 at 5 and in the top-piece 3 at 6. The shaft 4 is driven from any suitable source of power, as an electric motor 7, by means of belting 8, a worm 9, and a worm wheel 10 fast on the shaft 4. Worm wheel 10 rests on the lower bearing 5, which is a thrust bearing. Surrounding the shaft 4 and resting on the gear wheel 10 is a sleeve 11, which serves as a support for a rotatable spider 12, through which the shaft 4 extends. Concentric cylinders 13 and 14 are secured to a flat annular plate 15 on the spider 12, thus forming an annular tank 16 surrounding the shaft 4.

When the machine is in use, the tank 16 is filled with oil, and the transformer parts, in the tank 16, are then immersed in oil. The transformer comprises an annular magnetic core 17 supported by a delta-shaped yoke 18, see Fig. 4. Around the core 17 is the primary winding 19, and outside that is the secondary winding 20, the windings being distributed symmetrically with respect to the yoke 18. The yoke 18, with the core 17 and windings 19 and 20, are supported above the bottom plate 15 of the tank by a ring 21.

Each turn of the secondary winding 20 which comprises a comparatively few turns of large cable to carry heavy current, is connected at one side of the core 17 to an annular electrode 22, which is continuous, and at the other side to an outer electrode, 100 which comprises spaced sectors 23, see lower half of Fig. 4. Referring now to Fig. 1, the electrodes 22 and 23 are shown in vertical section as being held together by bolts

24, but electrically separated by heavy insulation 25. On each sector of the outer electrodes 23 is mounted a water cooled contact 27, and directly opposite on the inner electrode 22 is mounted a similar water contact 26, see Figs. 5, 6 and 8.

10 The electrodes 22, 23 may be supported above the tank 16 in any suitable manner, and as shown in Fig. 1, this support is obtained from an irregular casting 28 which surrounds the shaft 4 and rests on a shoulder formed on said shaft. This casting 28 covers the inner portion of the tank 16, leaving, however, a passage 28^a for cables, 15 as will be hereinafter described. Another casting 29 covers the outer portion of the tank, having an overhanging edge 29^a, and the castings 28 and 29 are secured together with the electrodes 22 and 23 between them, 20 by the bolts 24. This whole electrode structure forms a cap to the rotating part of the machine, said cap being generally inclined like a cone. The casting 28 has a ridge 28^b running completely around the machine, 25 which, together with posts 30 on casting 29, act as bearing supports for a plurality of clamping mechanisms, to be hereinafter described.

30 The cooling water is supplied to the machine through a gland 31, which delivers it to the passage 4^a inside the lower half of shaft 4, and in most locations no pump will be necessary, the local water pressure being sufficient. Passage 4^a is blocked at 32, and 35 just below that point a pipe connection, not shown, is tapped into shaft 4. From there the water desirably branches to cooling coils 34, which lead annularly around the tank 16, and also to a header 35. The header 35 has 40 a plurality of pipes 36 leading therefrom, which carry the water to all the outer electrodes 23 where it goes through passages 37 to the contacts 27. The water then leaves 45 the electrodes 23 by parallel passages 37^a, and back, by means of piping 38, to the inner electrode 22, see Figs. 1, 4 and 8. Similarly, in the electrode 22, the water goes to the inside contacts 26 through a plurality of 50 passages 39, and out again by a plurality of parallel passages 39^a to piping 40 and a header 41. The header 41 takes the collected water to the upper portion 4^b of shaft passage by means of piping 42. Similarly, the water that circulates through the piping 34 is led to the upper shaft passage 4^b by piping, not shown. In some heaters the piping 34 may be omitted, the piping 36 and 38 being sufficient to cool the oil in the tank 16. An outlet gland 43 on top of the shaft 4 takes the discharged water away from the machine.

60 It will be noted that the piping 36 from the distributing header 35 and also the piping 38, both lead electrically from one electrode to the other and pass around the core

17, so they act as an auxiliary secondary and increase the efficiency of the machine. In this connection, it is further noted that the inner electrode is not insulated from the machine as a whole, while the outer electrode segments are. Electric current is fed to the transformer primary 19 by means of collector rings 44. These rings are separated by insulating plates 45, and the structure as a whole is secured by means of bolts 46, inside of insulating tubes 47, to the spider 12. Of course, brushes of any usual sort, not shown, connect with the rings 44. From the rings 44 the current is led by heavy cables 48 between the shaft 4 and the inner cylinder 14 to the tank 16, where they connect to the primary 19.

10 Referring to Figs. 1 and 7, on the upper part of the shaft 4 is mounted a tap changing switch for the purpose of changing the voltage induced across the electrodes 22-23. It comprises a number of rows of switch jaws 49 arranged annularly on insulated disks 49^a, the number of the rows being equal to the number of electric phases used, in this case three. Each switch jaw 49 is connected to a tap on the primary 19 by a cable 50 which passes thereto through the sleeve portion 28^a of the irregular casting 28. Each switch jaw connects to a tap on the transformer primary 19, and jaws, vertically in line, connect to similar taps on each phase, see Fig. 7.

15 A three phase plug switch is supplied which can be inserted in any vertical row of jaws and in so doing connect as shown at 51, a pair of duplicate taps of each phase on the primary 19 together simultaneously. By moving the plug switch radially to the next vertical row of switch jaws, it is possible to 20 either lower or raise the induced voltage by adding or subtracting turns from the primary 19.

25 Referring particularly to Fig. 1, a main feed hopper 52 is located at the side of the machine. It has inclined bottom plates with a chute 53 leading from the low point of the hopper. An agitator 54, which oscillates about a pivot 55, driven by a connecting rod 56 and eccentric 57 on a shaft 58, pokes the rod stock into the chute 53 and prevents two or more pieces from arching over the entrance thereto. The walls of the chute 53 are not continuous, but have vertical gaps to allow of cleaning of the stock by grinding 30 wheels 59 and 60. As shown in Fig. 2, the wheels 59 and 60 are mounted on a shaft 61, which is held by suitable bearings, and derives its rotation from the motor 7 by means of a belt 62 and a pulley 63 on said shaft. Shaft 61 is threaded with both right and left threads, and the hubs of the grinding wheels 59 and 60 are threaded, and adjustably held in place by lock nuts 64 and 65, which are threaded oppositely to said hubs.

The shaft 58 is threaded in similar fashion, and besides the eccentric 57, a pair of pressure wheels 66 and 67 are mounted on it and adjustably secured by lock nuts. Shaft 58 is rotatably mounted on rockers 68 which can be adjusted relative to the stock by means of rods 69. Pressure springs 70, held by nuts 71 on said rods cause the wheels 66 and 67 to press against the stock, thus forcing the latter against the grinders 59 and 60.

The rockers 68 are pivoted on a shaft 72. Rotatably mounted on said shaft is a gear 73, which meshes with a gear 74 that is locked on shaft 58. A gear 73^a also on said shaft 72 meshes with a gear 75 fixed to a shaft 76 that is rotated in a manner to be described. Thus the pressure wheels 66 and 67 are rotated counterclockwise (Fig. 1), but at a much slower rate than the grinders 59 and 60, which, it should be noted, also revolve counterclockwise. See Fig. 9 for the above gearing.

Below the chute 53 is a cone 77. Grooves 78 formed in said cone remove the stock from the chute, piece by piece, and deposit it on a ledge 79, where it rolls by gravity into one of a series of buckets 80. The buckets 80 are mounted on endless chains that pass over sprockets 81, 81 mounted on a shaft 82 held by bearings 82^a at the top of the machine, over idler rolls 83 rotatably supported by brackets 84 at the side of the machine, and down to sprockets on shaft 76. As shown in Fig. 2, the shaft 82 is driven by a bevel gear 85 fast on it which meshes with a bevel gear 86 fast on the shaft 4. Thus the buckets and chains are driven, and serve to drive shaft 76. The gear 73 meshes with a gear 87 attached to the cone 77, and thus the latter is driven positively in timed relation to the buckets 80, see Figs. 1 and 3. The cone 77 and buckets rotate in counter-clockwise direction, Fig. 1.

The purpose of making the delivery drum 77 in the form of a cone is to keep the stock in the chute 53 out of parallel with the grinders, 59, 60, so as to prevent simultaneous grinding of individual pieces at more than one point.

The buckets 80 deliver the stock to a chute 88 at the top of the machine. See Figs. 1 and 2. Referring now to Figs. 5 and 6, each piece of stock is forced to an inclined position in the chute 88 by a ledge 89 in said chute. This is to force the stock to assume a position substantially parallel to an element of the conical cover parts 28 and 29 before it is picked up by the clamping mechanism. The bottom piece of stock in the chute 88 is held by a take off ledge 90 and a plurality of fingers 91 that are pivotally mounted on a shaft 92 and forced against the stock by springs 93.

Referring again to Fig. 1, shafts 94 are

rotatably held in insulated journals by the ridge portion 28^b and the posts 30. As best shown in Figs. 5, 6 and 8, these shafts hold the clamping means, which consists of pairs of equal pressure clamps 95 and 96 mounted 70 on the shafts 94, with members 97 between them. The latter are fast on the shafts 94, while the clamps 95 and 96, although pinned thereto, are capable of limited motion relative to shafts 94. Pins 98 pass through 75 the clamps 95 and 96 and between forked portion 99 on the members 97. The forked portions 99 do not tightly hold the pins, and consequently since the members 97 actuate the clamps, a slight play is allowed, which 80 insures equal pressure being exerted by the clamps on the stock.

Pressure is supplied to the clamps from helical springs 100 wound on the clamp shafts 94. The pressure can be adjusted by 85 means of toothed clutches 101, 102, the parts 101 being fixed to the shafts 94 and the parts 102 being free on the shafts, but fixed to the helical springs 100. Triggers 103 fastened to the shafts 94 are actuated by a stationary 90 cam 104 and thus open the clamps to discharge the heated stock and receive a new piece at each rotation of the main shaft 4. Hammers 105 pivoted on shaft 92 rap each 95 piece of new stock in position. Said hammers have weighted portions 106.

The sequence of operation and the exact manner in which the stock is transferred is as follows:

The stock, which may be placed in the 100 hopper 52 in large quantities, having entered the chute 53, is polished at those points where it will short-circuit the contacts 26 and 27. It has been noted that the space between the pressure wheels 66 and 67 and the 105 grinding wheels 59 and 60 is adjustable by means of the rockers 68. This permits the machine to heat various diameters of stock.

As the cone 77 revolves, the groove 78 therein removes the pieces of stock one by 110 one from the chute 53 and transfers them to the buckets 80, which, as already described, move in exact timed relation to said cone. The buckets 80 transfer the stock to the overhead chute 88, where it is forced 115 to assume a position substantially parallel to the shafts 94, as already described. Since the chain of buckets is driven from the main shaft 4, the stock can be delivered to the chute 88 at the same rate at which it is taken 120 therefrom, and thus the chute 88 will never either be clogged with stock, or run short thereof, so long as the main hopper 52 is kept supplied.

Referring now to Fig. 6, it will be seen 125 that as the clamps 95, 96 approach the take-off ledge 90, the triggers 103 engage the stationary cam 104 and so, by partial rotation of the particular shaft in question, 94, the clamps 95, 96 are opened up. The bot- 130

tom piece of stock is consequently moved against the fingers 91, which are forced open to the dotted line position shown in Fig. 6; during this time the trigger in question, 5 103, is moving on the long inclined portion of the cam 104 and thus the clamps 95, 96 are slowly closing. The next piece of stock in the chute 88, is at this time, held from falling out of said chute by the long back portions 95^a, 96^a of the pressure clamps, as will 10 readily be seen from an inspection of the dotted line position thereof in Fig. 6. As 15 these portions 95^a, 96^a leave the chute 88, the fingers 91 snap closed in response to the action of the springs 93 and hold the 20 next above piece of stock on the take-off ledge 90.

The receding portions 95^a, 96^a of the 25 clamps just ahead of the one that is taking a piece of stock, lift up the hammer 105, which, owing to the weighted portion 106, strikes the piece of stock which has just 30 been clamped against the water cooled contacts 26, 27 a sharp blow, thus insuring that the piece of stock is properly seated and in 35 electrical connection to short-circuit said contacts 26, 27.

Of course, the lifting of the clamps 95, 40 96 from the contacts 26, 27 releases the 30 heated piece of stock when it has made a full circuit of the machine, and thereupon it drops down into any sort of receiving device, which is preferably provided with a ledge 107, whence it may be taken to perform 45 an operation thereon, such as heading or drop forging. A depression 108 in the cam 104 opens the clamps 95, 96, then allows them to spring closed for an instant. This insures that the heated piece of stock will 50 drop out even if it has been slightly welded to one of the clamps 95, 96.

Figs. 10, 11 and 12 show a modification of the feeding and cleaning mechanism. The 55 hopper 109 of the modification is desirably mounted on the top piece 3 of the machine. This hopper 109 is adapted to deliver stock by gravity to a revolving cage, generally indicated by the numeral 110, the details of construction of which are shown in Fig. 12. Said cage 110 is driven from the shaft 4 in the following manner: The shaft 4 provides a bevel gear 111 similar to the bevel gear 86 used in connection with the other modification, but facing upwardly. Bevel gear 111 drives a bevel gear 112 which is mounted on an horizontal axis. Gear 12 is connected by a short shaft 113 to a spur gear 114, said shaft 113 being journaled in a bearing 115 provided by a stand 116, whereby the two gears 112 and 114 are supported. The spur gear 114 meshes with a gear 117 which is keyed to the cage 110.

Said cage 110 comprises a pair of end plates 118, 119 between which extend a plurality of bars 120. The end plates 118

and 119 are horizontally journaled in bearings 121, 122 provided by stands 123 and 124 fastened to the top piece 3. The hubs of the end plates in turn enclose a pair of roller bearings 125 and 126. Journaled 70 in said roller bearings is a shaft 127 which is thus supported coaxially with the cage 110, but is adapted to be rotated independent thereof. The shaft 127 is rotated at a high rate of speed in any suitable fashion, 75 as by means of a motor 128 having a pulley which by a belt 129 drives a pulley 130 fastened to said shaft 127.

Adjustably fastened to the shaft 127 between the plates 118 and 119 (as by a set 80 screw 131) is a hub member 132. Said hub comprises a mounting for a pair of grinding wheels 133 and 134, which are held in place for example, by bolts 135 screwed into leaded holes 136 in one of said grinding 85 wheels.

The end plate 119 supports a long sleeve 137 which surrounds the shaft 127 but does not touch it. Said sleeve 137 provides means for carrying and longitudinally adjusting 90 a plate 138 provided with fingers 139 extending between the bars 120 and with a cylindrical ledge 140. The plate 138 has a pair of ears 141, 141 which are clamped by bolts 142, 142 to a split collar 143, this 95 constituting the means for adjusting the plate 135 longitudinally on the sleeve 137.

Above the cage 110 is a chain 144 composed of flat links and pins. This chain is supported at one end by a bracket 145 fastened, for example, to the hopper 109. At the opposite end the chain is fastened to a bell crank lever 146 which is pivotally mounted at 147 on a bracket 148. Said bracket 148 is in turn supported from the 105 top piece 3 by a large bracket 149.

The top of bell crank lever 146 pivotally connects to a forked link 150. A spring 151 is attached to the other end of said link, and by means of a threaded rod 152, passing through a short bracket 153 and adjustably held therein by nuts 154, the spring 151 is anchored to the hopper 109.

This feeding and cleaning means operates as follows. The rod stock clearly shown in 115 Fig. 11 is delivered by gravity from the hopper 109 to a discharge ledge 152 of said hopper. By means of a baffle 155 in the hopper, which can be adjusted longitudinally, the stock is delivered to the ledge 152 between 120 the plate 118 and the adjustable plate 138. As the cage 110 revolves in a counterclockwise direction, Fig. 11, a piece of stock is 125 picked up by each bar 120, a single piece resting between adjacent bars. The bracket 125 145 prevents more than one bar per space from being picked up, the grinding wheels 133 and 134, also the ledge 140 prevent the stock from falling through and the fingers 139 hold the stock in proper longitudinal 130

position. As the cage rotates, the stock is resiliently held in place by the chain 144, and the grinding wheels 133 and 134 which rotate rapidly, clean the stock at those places 5 where the contacts will be made in the heater.

When the stock has travelled a half revolution with the cage 110, it reaches a chute 88^a and is discharged into it. It will be 10 noted that the cage 110 is driven in timed relation to the shaft 4, and hence a piece of stock is delivered into the chute 88^a for each one taken therefrom by the automatic clamps previously described. The gears 111, 15 112, 114 and 117 are designed to give this result. In this manner, the chute 88^a will always contain some stock, and will never overflow. In starting the machine, the chute 88 or 88^a may desirably be given a surplus 20 of a few pieces.

I claim:

1. In a rotary metal stock heater, a tank mounted to rotate on an axis, annular electrodes supported by said tank, a magnetic core in said tank, and primary and secondary 25 circuits surrounding said core, said secondary being electrically connected to said electrodes.

2. In a rotary metal stock heater, an annular rotatable tank, annular electrodes supported by said tank, a magnetic core in said tank, and primary and secondary circuits surrounding said core, said secondary being electrically connected to said electrodes. 30

3. In a rotary metal stock heater, a tank mounted to rotate on an axis, annular electrodes supported by said tank, a magnetic core in said tank, a primary circuit surrounding said core, and a secondary composed in part of cooling pipes, also surrounding 40 said core, said secondary being electrically connected to said electrodes.

4. In a rotary metal stock heater, a tank mounted to rotate on an axis, annular electrodes supported by said tank, contact members connected to said electrodes, and cooling means for said electrodes and contacts, comprising pipes leading through said tank, whereby the liquid in said tank is also kept 50 cool.

5. In a rotary metal stock heater, a tank mounted to rotate on an axis, annular electrodes supported by said tank, a magnetic core in said tank, primary and secondary 55 circuits surrounding said core, said secondary being electrically connected to said electrodes, and cooling pipes to conduct water extending into said tank and leading to said electrodes, whereby to cool the liquid in said tank and directly cool said electrodes.

6. In a rotary metal stock heater, a tank mounted to rotate on an axis, a generally conical cap structure for said tank providing electrodes, transformer means in said tank 60 to create a heating current when said elec-

trodes are short circuited, conveying means to convey pieces of rod stock above said cap, and individual clamping means spaced about said generally conical cap structure adapted to remove stock from said conveying 70 means, whereby stock is automatically transferred from said conveying means to said cap structure to short circuit said electrodes as said tank rotates.

7. In a rotary metal stock heater, an annular tank mounted to rotate on an axis, an electrode structure mounted on said tank, providing a plurality of pairs of contacts, transformer means in said tank to convey heating current to said electrode structure, 75 and piping in said tank conveying coolant both to said contacts, the electrode structure, and to the liquid in said tank, whereby to cool said electrode structure, contacts, and the transformer means. 80

8. In a rotary metal stock heater, an annular tank mounted to rotate on an axis, an electrode structure mounted on said tank, providing a plurality of pairs of contacts, 90 transformer means in said tank to supply heating current to said contacts, and piping in said tank constituting means for cooling the transformer, electrodes, and contacts, and also comprising, in part, the secondary 95 of said transformer.

9. In a rotary metal stock heater, a hollow vertical tube, an annular tank surrounding said tube and rotatable therewith, an electrode structure supported by said tank and providing a plurality of pairs of contacts, 100 piping in said tank for circulating cooling liquid therethrough, whereby to keep the coolant liquid which is free in said tank cool, and passages in said hollow tube connected to said piping. 105

10. In a machine of the class described, a hopper, a rotary heater providing a plurality of angularly spaced electric heating units, conveying means for delivering pieces 110 of stock to said heating means in timed sequence, and automatic grinding means associated with said conveying means to grind each piece of stock prior to its delivery to the heating means.

11. In a machine of the class described, a hopper, a rotatable electrode structure providing a plurality of pairs of contacts, conveying means for conveying pieces of stock in timed sequence from said hopper to a position above said rotatable electrode structure, grinding means adapted to successively grind each piece of stock, means controlled by rotational movement of said electrode structure for transferring pieces of stock from said conveying means to positions between pairs of contacts, and further means for removing pieces of stock from said contacts after being heated a predetermined amount. 120

12. In a machine of the class described, 125 means for successively grinding and feeding

a plurality of pieces of stock, a rotatable element providing a plurality of pairs of contacts, and transferring means automatically operable to transfer said stock from said feeding means to said rotatable element.

13. In a machine of the class described, a hopper, a rotatable cage providing spaced gaps for the reception of pieces of stock, means to hold the stock in said gaps, and grinding wheels inside said cage to clean said stock.

14. In a machine of the class described, a hopper, a rotatable cage providing spaced

gaps for the reception of pieces of stock, means to hold the stock in said gaps, and grinding wheels mounted inside said cage and concentric with it, to clean said stock.

15. In a machine of the class described, a hopper, a rotatable cage providing spaced gaps for the reception of pieces of stock, an adjustable end plate to vary the length of said gaps, a chain to hold the stock in said gaps, and grinding wheels mounted inside said cage and concentric with it, to clean said stock.

ERNEST S. JEFFERIES
